UNITED STATES PATENT OFFICE.

CHARLES E. DURYEA, OF PHILADELPHIA, PENNSYLVANIA.

MOTOR-VEHICLE.

1,208,111.

Specification of Letters Patent. Patented Dec. 12, 1916.

Application filed May 8, 1915. Serial No. 26,893.

To all whom it may concern:

Be it known that I, CHARLES E. DURYEA, a citizen of the United States of America, and resident of Philadelphia, county of Philadelphia, State of Pennsylvania, have invented certain new and useful Improvements in Motor-Vehicles, of which the following is a specification.

This invention relates to certain new and useful improvements in motor vehicles and more particularly to the drive mechanism thereof.

The present invention has for its objects among others to provide an improved roller drive mechanism embodying a slip or flexible joint between the motor shaft and the roller drive members.

I provide for a multiplicity of drives forward and one reverse, with suitable mechanism whereby the roller drive may be easily controlled. I pivot the rear frame to the chassis frame so that in passing over obstacles the rear wheels can rise without lifting the body, suitable springs being interposed to permit this action and yet carry the load. The motor is supported on parts of the rear frame and the controlling means on the chassis frame. I provide universal or slip joints in a composite shaft which permits swinging fore and aft, as well as shifting in and out, with suitable means for producing such movements, so that I may bring any desired friction drive roller into any desired ring plane and then bring them into operative contact.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a plan view with parts in section, portions removed and other parts broken away, showing one form of embodiment of my present invention. Fig. 2 is a vertical longitudinal section on the line 2-2 of Fig. 1 looking in the direction of the arrows. Fig. 3 is a substantially central section through the drive rollers with the shaft broken away. Fig. 4 is a side elevation on an enlarged scale with the motor shaft in section, showing the bell crank. Fig. 5 is a vertical section on the line 5-5 of Fig. 4

looking in the direction of the arrows. Fig. 6 is a vertical section on the line 6-6 of Fig. 2 looking in the direction of the arrows. Like numerals of reference indicate like parts throughout the several views. 60

Referring to the drawings, the motor (not shown) is placed approximately central at the rear end of the vehicle with its shaft parallel to the rear axle 1 of the vehicle and shaft extensions 2 reaching nearly to the wheels, near the rims. (If the front wheels are to be driven, the placing is at the front, of course, and in cases where it is desired to drive all four wheels, two motors are used and placed one at the front and the other 70 at the rear with practically the same control and drive devices; but in that event a different steering must be used, such as king bolts at the center of the wheel axles and means for turning the axles around a vertical center.) On the ends of the motor shaft extensions 2 are grooved rollers 3 having two or more grooves, in this instance three, 9, 10 and 11. These shaft extensions are carried in bearings 4 movably mounted on 80 the rear frame 5. The grooved rollers 3 may be brought into the plane of ridge-shaped rings 6 attached to the wheels 7. It is preferable to arrange the rotation of the motor shaft the same as the wheel direction and use the ring 6 with the roller 3 inside of it for forward driving and fit a second ring 8 nearer to the wheel hub than the roller 3 and drive on the outer edge of the ring 8 for reverse motion of the vehicle. 90

Of course, if the motor is of a type that may be reversed, then one of the rings may be dispensed with and one ring only used.

As shown in Fig. 1, the largest groove 9 of the roller 3 is shown in contact with the ring 6 which corresponds to the usual highest speed forward. 95

Since the bearing 4 is movably mounted on the frame 5, it may be shifted backward by any suitable means and the contact released when the vehicle will be free from the motor. It will then be free to stop or be pushed or moved in any suitable manner without any mechanism being turned, except the wheels 7 of the vehicle. It is to be noted that a further motion of the bearing backward brings the smallest groove 11 of the roller 3 into contact with the ring 8 and this causes the motor rotating the shaft extension 2 to drive the vehicle in a direction the re- 105

verse of that driven when the roller 3 contacts with the ring 6. This sliding of the bearing 4 naturally throws the shaft extension 2 out of its original alignment, which 5 is permitted by the use of any suitable form of universal or flexible joint. A joint of common shape is shown at 12 having a flexible disk between its opposed members. It is further constructed with a slip joint 13 10 formed by inserting the squared end of the shaft extension 2 into the outer member of the joint 12, so that the shaft extension may be moved toward or from the plane of the wheel 7. The exact construction and arrangement of the slip joint 13 or the universal joint 12 is not of great moment so long as some device is provided to perform the functions shown. In the present instance, the flexible joint is shown as comprised of a member 14 adapted to be flexed, the member 15 which receives the squared end of the shaft extension being connected therewith in any suitable manner, as at 16, 20 the other member 17 being connected with the adjacent end of the motor shaft, as shown in Fig. 1. It is, therefore, evident that the slip joint 13 and the movable bearing 4 permit the shaft extension 2 and the roller 3 to be shifted from the plane of the 25 wheel 7 and a smaller groove of the roller 3 to be brought into the plane of the ring 6, and a lower gear ratio to be established between the engine and the driven wheel 7. The roller 3 while shown as having three 30 grooves of various sizes, it is evident a less or greater number may be used according to the requirements of the vehicle. When the smallest groove of the roller engages the ring 6, it is quite evident that the motor 35 makes the most turns for a given number of revolutions of the wheel and a most powerful drive results. Means for shifting the shaft extension 2 and the roller 3 on the shaft extension 2 are found in the slidable bearing 40 4 which carries the shaft extension 2, in combination with the various rods and levers now to be described. The fore and aft movement of the bearing 4 is caused by a rod 18 attached to the bearing at one end and at 45 the other to a more or less vertical crank 19 on the outer end of the torsion bar 20. At the center of this bar 20 is a bracket 21 in which the tube lever 22 is fixed and this 50 tube lever 22 serves as a lever by which the bearing 4 and the mechanism it carries may be moved forward and back. A ratchet 23 carried by this lever serves to hold this lever in place when in neutral or in forward driving positions. It is not customary to lock 55 it in the reverse position, but the operator usually holds it in place while the vehicle is reversing. The ratchet 23 may be held up against the tooth 24 by a spring 25 and cause it to engage when the lever 22 is moved 60 forward, but the ratchet may be disengaged 65

by depressing the rod 26 which passes up inside the tube lever 22 and out at the top of the handle 27 provided for the operator's convenience. This handle 27 and a short lever 28 just below it are fastened to a tube 70 29 which passes down inside the tube 22 but outside of the rod 26. To the lower end of this tube 29 is fixed a crank 30 having two ends or eyes 31 and 32, into which are fixed the ball ends of the rods 33 and 34 passing 75 one to each side of the vehicle and engaging the bell cranks 35 and 36 which are, in turn, each pivoted to a sliding grip 37, as at 38, and to the bearing 4, as at 39. This grip 37 can slide fore and aft on the frame 5, but cannot slide appreciably on the frame 5 crosswise. It, therefore, acts as a fulcrum for the bell crank 35 and causes it to shift the bearing 4 laterally when the handle 27 and lever 28 are turned. The width of the bearing 4 between its bolts 40, 40 is such that when it is shifted as far one way as it may go laterally, the larger groove 9 of the roller 3 is in the plane of the ring, as shown in Fig. 1, and when shifted to its limit laterally the other way, the smaller roller groove 11 is in the plane of the ring 6. Thus the operator need not pay attention to the shifting so far as the extreme speeds are concerned, but simply shifts to the limit. When 80 the intermediate speed or speeds are desired, the lever 28 is set at some predetermined position, as, for example, pointing straight to the rear, as shown in Fig. 2. If preferred, a segment with notches in it for the location 85 of the lever 28 can be provided in any well known manner. The motor and shaft extensions forming the driving mechanism are located on the rear frame 5 as before stated, the motor being fixed thereon and not intended to be moved except with the frame. The controlling devices shown, as well as the motor controls, not shown, are located in the body 90 of the car or at least near to the rider where he can operate them easily and handily. The rear frame is pivoted to the body at 41, so that the rear wheels in passing over obstacles can rise without lifting the body, and springs 42 are interposed to permit this 95 action and yet carry the load. These springs may be of any well chosen form, but I show a bar 43 under the body frame. A second bar 44 rests on top the rear frame member and bolts 45 pass through these bars and up 100 far enough to extend through the springs 42 and take adjusting nuts on their top ends. By means of these adjusting nuts, the tension of the springs can be quickly made greater or less and new springs or springs 105 of different strength can be substituted. Of course, it is understood that the motor (not shown) rests on parts of the rear frame 5 and that the forward end of the motor support may and is also pivoted to the rear end 110

of the body frame in a similar manner. The rods 33, 34 and 18, 18 are placed substantially in the axis of the pivots 41 and are, therefore, but slightly affected by the fact 5 that the rear frame moves angularly about the pivots 41, and, in practice, it is common to pass them through holes in the body or supports practically in the line of the axis of the pivots 41, so that they spring as the 10 springs 42 come into action and yet retain the same relative length or distance between the controlling parts and the controlled parts to the end that the contact pressure of the drive rollers against the drive rings may be 15 practically maintained. While it is evident that springs can be inserted in the rods 18, 18, so as to secure a spring tension on the driving contact mentioned, it is also evident that the torsion bar 20 is not perfectly rigid, 20 but has some torsional elasticity and so serves just as a spring would do. This action compensates for any inequality in radial lengths or for any reasonable lack of accuracy in the shape of the drive rings 6 and 8 25 and goes far to make an efficiently acting drive. It also conduces to a smooth clutch action when starting the vehicle by gradually engaging the contact surfaces.

It is customary to start the vehicle by 30 starting the motor first and then setting the rollers into contact with the driven rings gradually just as any friction clutch is usually set; and the lever 22 is used to do this; but while driving it is often desired to release the driving contact temporarily without shifting the gears or going to the trouble of releasing the ratchet 23 by the use of the hand applied to the handle 27. I, therefore, provide a support for the tooth 24 on a lever 40 pivoted to the frame of the body at the lower front edge of the seat or similar suitable place. The lower end of this lever 46 comes against a stop 46^a when it is as far forward as desired, but it is free to be forced 45 backward and carry the tooth 24 backward sufficiently far to release the driving contact between the rollers 3 and the rings 6 because carrying the tooth 24 backward allows the ratchet 23 to follow backward and 50 the lever 22 with its parts follows until there is little or no driving pressure. The actual distance required to release the driving pressure is not great, since the contact metals are hard and but a slight movement insures 55 a firm contact. The means for forcing the lever 46 backward are shown in Fig. 2 where the rod 47 pivoted at 48 to the said lever, connects with a pedal lever 49, pivoted at 50, to a bracket 51 fastened to the inclined floor 52 of the vehicle of which 53 is the seat. A spring 54 holds the pedal 55 away from the floor and returns the parts to their original position when they have been temporarily shifted by pressure on the pedal. 60 In short, the releasing and engaging of the

power under the action of the clutch pedal is practically like the clutch action found in automobiles of more conventional design.

Thus far this device has been described as needing manual power to set the drive 70 rollers into contact with the driven rings 6 and 8, but only part of the power need be applied by the operator in his forward movement of the lever 22. The remainder can be stored in springs by a rearward 75 movement of the lever 22. In Figs. 2 and 4 is shown a rearward extension 56 of the bearing 4. On the rear frame 5 are two lugs or supports 57, 58 for springs 59, 60. These springs can be of any preferred shape, but 80 should be so formed that they bear on points or knife edges only so as to permit the bearing 4 and its extension 56 to move freely except as affected by the pressure of the springs 59, 60 which are under their greatest compression when in a right line or perpendicular to the fore and aft movement of the bearing 4. Now it is evident that if the bearing 4 be carried forward of the neutral position which coincides with the perpendicular and balanced pressure position of the springs, they will tend to force the bearing farther forward. And if carried backward, they will force the bearing backward. 85 Thus they assist in securing the contact pressure necessary to drive the vehicle, but the operator must overcome their tension when he throws the lever 22 to bring the rollers into neutral position. When the foot clutch is used, it is evident that the pressure exerted by the springs 59, 60 must not be great enough to drive the vehicle or the clutch action, as above described, will be inoperative. 90 It is evident that the pedal 55 can be caused to positively throw the parts backward, if it is so desired to build it and in this case the springs 59, 60 may be strong enough to drive the vehicle by their pressure, but the preferred arrangement is as shown and the springs simply assist to secure the pressure. 95 The arrangement of the springs is such that their fore and aft action is practically nothing at the neutral position and increases each side thereof, so that when the shaft extension 2 and roller 3 are swung farthest forward, the spring pressure is greatest as is, of course, the need for pressure due to the fact that such position is only used when there is hard labor for the vehicle and when the engine leverage with relation to the driven wheels is greatest. It is evident that several forms and applications of springs 100 may be used for this purpose.

It will be noted that when the shaft extensions 2 are moved so that the larger groove 9 is in coöperative relation with the ring 6, the groove 11 is substantially in alignment with the ring 8, the groove 10 being neutral. When the shaft extensions are 105 moved inward and thence moved on their 110 115 120 125 130

universal joints so that the grooves 10 are in coöperative relation with the ring 6, the grooves 9 and 11 are neutral, the groove 11 being used both for reverse and low.

5 From the above it will be seen that I have devised a simple, cheap, yet efficient and durable, easily operated and controlled roller drive mechanism, and while the structural embodiment of the same as herein disclosed 10 is what I at the present time consider preferable, it is evident that the same is subject to various changes, variations and modifications in detail, proportion of parts, etc., without departing from the spirit of the invention or sacrificing any of its advantages. I, therefore, do not intend to restrict myself to the exact construction hereinbefore set forth, but reserve the right to make such changes, variations and modifications as 15 20 come properly within the scope of the protection prayed.

What is claimed as new is:—

1. An automobile chassis frame or body frame and a rear wheel frame pivoted there- 25 to to rise and fall independently of the said frame, a motor mounted upon and above said rear frame, friction driving mechanism on the rear frame coöperating with the rear wheel and controlling means therefor on the 30 chassis frame.

2. An automobile chassis frame or body frame, and a rear wheel frame pivoted thereto to rise and fall independently of the said frame, a friction drive on the rear 35 frame and controlling means therefor on said chassis frame.

3. An automobile chassis frame or body frame, and a rear wheel frame pivoted there- 40 to to rise and fall independently of the said frame, a friction drive on the rear frame and controlling means therefor on said chassis frame, said pivoted frame adapted to support a power plant.

4. An automobile body frame, a rear 45 wheel frame pivoted thereto to rise and fall independently of said frame and to support a power plant, drive mechanism on the rear frame, controlling means therefor on the chassis frame, and springs interposed be- 50 tween said frames in proximity to the pivot of said frames to permit such rise and fall and yet carry the load.

5. An automobile body frame, a rear frame pivoted thereto, a power plant sup- 55 ported thereby, roller drive mechanism on the rear frame, means on the chassis frame for controlling the same and pressure-assisting means disposed adjacent the rear axle and operable in conjunction with the 60 movement of said roller drive mechanism to assist in securing the necessary contact pressure to drive the vehicle, said pressure-assisting means being independent of the power plant.

6. An automobile body frame, a rear

wheel frame pivoted thereto, roller drive mechanism supported on the rear frame, pressure-assisting springs adjacent the rear wheels, and control mechanism therefor supported on the automobile body frame, said 70 springs being independent of the body-supporting springs.

7. An automobile body frame, a rear wheel frame pivoted thereto to rise and fall independently of the body frame, roller 75 drive mechanism supported on the rear frame, control mechanism therefor supported on the automobile body frame and means on the rear frame controlled by the actuation of the roller drive mechanism and ar- 80 ranged to assist in securing contact pressure necessary to drive the vehicle.

8. An automobile body frame, a rear wheel frame pivoted thereto, a roller drive mechanism on the rear wheel frame, and 85 universal joints in the motor shaft in the connection with the power plant to permit the application of power to the wheels on said rear frame.

9. A roller drive mechanism, a motor 90 shaft by which said roller drive mechanism is driven, movable shaft extensions, bearings therefor in alinement with the motor shaft and movable endwise thereof, and universal connections in the shaft between the roller 95 drive mechanism and the motor shaft.

10. A rear wheel frame adapted to support a motor in fixed relation thereon, a chassis frame, said frames being pivotally mounted to rise and fall independently of each other, movable bearings, and shaft extensions carried by said bearings, a lever and connections for bringing the driving members in contact with the driven members of the roller drive mechanism, by movement of 105 said bearings.

11. In a friction roller drive mechanism for motor vehicles, a pivoted hand control for causing driving engagement of the rollers and a foot control for temporarily 110 releasing said driving engagement.

12. In a roller drive mechanism embodying relatively fixed rings and relatively movable grooved rollers for engagement therewith, an elastic member for holding a frictional driving surface against a driven one, the same embodying a torsion bar and connections between the same and the said rollers.

13. In a device of the character described, 123 a power plant shaft, and shaft extensions therefor and a roller drive mechanism embodying a plurality of rollers, one set of which are carried by said shaft extensions, and universal and slip joints permitting 125 bringing any desired roller into the plane of any desired coöoperating member and then bringing said member and roller into contact.

14. A roller drive mechanism embodying 130

endwise movable motor shaft extensions, and universal and slip joints between said extensions and the motor shaft.

15. A roller drive mechanism embodying 5 endwise movable motor shaft extensions, means for moving said extensions universal and slip joints between said extensions and the motor shaft, and movable bearings for said extensions.

10 16. A roller drive mechanism embodying endwise movable motor shaft extensions, means for moving said extensions universal and slip joints between said extensions and the motor shaft, movable bearings for said 15 extensions, and means for moving said extensions.

17. In a device of the character described 20 embodying a friction roller drive mechanism, hand-operated gearless means for setting the rollers into contact with the driven rings, and foot-operated means for releasing such driving contact of said rollers and rings temporarily without shifting the gears.

18. In a device of the character described, 25 roller drive mechanism, controlling means therefor, and yielding pressure assisting means inactive at neutral position and active

either side of neutral position and coöperating with said roller drive mechanism, said pressure-assisting means being independent 30 of the power plant.

19. An automobile body frame, a rear wheel frame pivoted thereto near the rear end of the latter and forward of the rear axle and adapted to rise and fall independently of said body frame, and a power plant supported by said rear frame to the rear of the connection between the two frames.

20. An automobile body frame, a rear frame pivoted thereto, a power plant supported thereby, roller drive mechanism on the rear frame, means on the chassis frame for controlling the same, and pressure-assisting means forward of the rear axle and operable in conjunction with the movement 40 of said roller drive mechanism, said pressure-assisting means being independent of the power plant.

Signed by me at Philadelphia, Pa., this 19th day of May, 1914.
